HOLDER

Stephen T. Leonard and David O'Neill,
New York, N. Y.

Application August 7, 1940, Serial No. 351,764

2 Claims. (Cl. 248—33)

Our invention relates to improvements in holders, the principal object in view being to provide an inexpensive, lightweight, and serviceable device for use on restaurant counters, tables, and the like, for holding menus in upright position for ready removal and replacement, and which is also designed for holding salt, pepper, and sugar shakers within easy reach and in a manner such that the contents thereof will not be spilled on the counter or the table, if the shakers are accidentally upset.

To the accomplishment of the above, and subordinate objects presently appearing, a preferred embodiment of the invention has been illustrated in the accompanying drawing, set forth in detail in the succeeding description, and defined in the claims appended hereto.

In said drawing:

Figure 1 is a view in top plan, partly broken away, of the preferred embodiment of our invention, and

Figure 2 is a view in transverse section taken on the line 2—2 of Figure 1.

Referring to the drawing by numerals, the holder of our invention, in the illustrated embodiment thereof, comprises a substantially rectangular, one-piece tray 1, of suitable metal, having a bottom 1, a front wall 2, side walls 3, and a back 4 comprising parallel longitudinally extending walls 5, spaced apart laterally, and a straight-sided trough 6 extending longitudinally between said walls 5 and connected thereto by a pair of front and rear top webs 7 and 8. The front wall 2, side walls 3, and back walls 5 extend below the bottom 1 and support the latter, and the back walls 5 extend above said bottom 1 equidistantly so as to locate the open top of the trough above said bottom. The front top web 8 underlies and is spaced from a top web 9 extending from the adjacent back wall 5 and forming with said web 8 a horizontal guideway 10 in the back 4 in front of the trough 6 at the top thereof. A vertically disposed clamping plate 11 is provided in the trough 6 for cooperation with the rear side thereof to clamp the lower edges of menus, not shown, therebetween to hold said menus in upright position, said plate having a right angled upper edge flange 12 slidably fitting in said guideway so that said plate is mounted for adjustment forwardly and rearwardly into different clamping positions. A threaded stud 13 upstanding from the flange 12 and extending through a transverse slot 14 in the web 9, with a wing nut 15 thereon, provides

for adjusting said plate 11 into different set positions.

The bottom wall 1 is provided with a large, annular, open bottomed socket 16 in the transverse center thereof for seating a sugar shaker, not shown, therein. A pair of similar, but smaller, sockets 17 are provided in said bottom 1 upon opposite sides of the socket 16 and forwardly of the latter for salt and pepper shakers, not shown.

As will be seen, one or more menus may be yieldingly clamped in the trough 6 for ready removal or replacement and the open bottom sockets 16, 17, provide for the contents of the shakers when spilled on the tray being brushed out of the sockets onto the counter or table to be confined under the tray so that they will not be scattered over the same.

The foregoing will, it is believed, suffice to impart a clear understanding of our invention without further explanation.

Manifestly the invention, as described, is susceptible of modification without departing from the inventive concept, and right is herein reserved to such modifications as fall within the scope of the subjoined claims.

What we claim is:

1. A holder for use on a counter, or the like, to hold menus comprising a rectangular base, a double-walled back structure rising above said base and formed with a longitudinally extending straight-sided trough therein adapted for standing menus in the same, and a longitudinally extending clamping plate in said trough mounted therein for adjustment into different set positions to yieldingly clamp the menus to one side of the trough.

2. A holder for use on a counter, or the like, to hold menus comprising a rectangular base, a double-walled back structure rising above said base and formed with a longitudinally extending straight-sided trough therein adapted for standing menus in the same, and a longitudinally extending clamping plate in said trough mounted therein for adjustment into different set positions to yieldingly clamp the menus to one side of the trough, the mounting for said plate comprising a right-angled flange thereon, and a horizontal guideway in said top structure, said flange being slidably mounted in said guideway, and means to establish the set positions of said plate.

DAVID O'NEILL,
STEPHEN T. LEONARD.
